DESIGN FOR A DECK OF PLAYING CARDS

Alfred M. Voit, Louisville, Ky.

Application July 18, 1942, Serial No. 107,601

Term of patent 7 years

To all whom it may concern:

Be it known that I, Alfred M. Voit, a citizen of the United States, residing at 1930 South Fourth Street, Louisville, Jefferson County, Kentucky, have invented a new, original, and ornamental Design for a Deck of Playing Cards, of which the following is a specification, reference being had to the accompanying drawing, forming part thereof.

Figure 1 shows face views of certain cards of the deck embodying my new design;

Figure 2 shows the back of the cards.

The cards have no appreciable or substantial thickness.

The cards in each suit numbered from 2 to 9 are conventional, that is the number of indicia on each card corresponds to the figure in the corners of the cards and the indicia are arranged in the same conventional way as ordinary playing cards, the indicia corresponding to the indicia shown on the ten spot of each suit in Figure 1.

I claim:

The ornamental design for a deck of playing cards, substantially as shown, and described.

ALFRED M. VOIT.
